UNITED STATES PATENT OFFICE.

CLAYTON E. FREDERICKSON, OF CHICAGO, ILLINOIS, ASSIGNOR TO FREDERICKSON ENGINEERING CORPORATION, OF CHICAGO, ILLINOIS, A CORPORATION OF DELAWARE.

DERRICK.

1,252,336.

Specification of Letters Patent.

Patented Jan. 1, 1918.

Application filed May 29, 1916. Serial No. 100,497.

To all whom it may concern:

Be it known that I, CLAYTON E. FREDERICKSON, a citizen of the United States, residing at Chicago, in the county of Cook 5 and State of Illinois, have invented new and useful Improvements in Derricks, of which the following is a specification.

This invention relates to structural steel towers or derricks of that type particularly employed as part of the equipment for sinking oil, gas, and like wells, and such derricks generally comprise four upwardly converging corner posts connected together around the four sides of the derrick by horizontal struts and diagonal tie-rods, the corner posts each being made of an equal number of sections placed in vertical or longitudinal alinement and rigidly secured together at the ends thereof by joint plates and clamp 20 bolts.

Among the objects of my invention is to improve the construction of the joint members so that the derrick parts will be permitted to yield or give vertically, relatively 25 to each other, under the vertical loads and strains to which the derrick may be subjected while in use and relieve the clamp bolts associated with said joint members from all of such strains. A further object 30 of my invention is to provide a joint member that will maintain the clamped ends of the post sections in place so that the opposed ends of the post sections will be prevented from slipping or moving past each other and 35 effecting the shearing of the clamp bolts. Other and further objects of the invention will appear from the following specification.

The invention consists further in the matters hereinafter described and more particularly pointed out in the appended claims.

In the accompanying drawings:

Figure 1 is a perspective view of a structural steel tower or derrick of the kind referred to and having the several parts there- 45 of connected together by joint members embodying the features of my invention;

Fig. 2 is an enlarged horizontal sectional view taken on line 2--2 of Fig. 1;

Fig. 3 is a vertical sectional view taken 50 on line 3--3 of Fig. 2;

Fig. 4 is a side elevational view of the parts shown in Fig. 2;

Fig. 5 is a front elevational view of the parts shown in Fig. 2; and

Fig. 6 is a perspective view of one of the 55

joint members removed from the derrick structure.

In Fig. 1 of the accompanying drawings, I have shown, as completely erected, a structural steel tower or derrick of the type now 60 customarily employed as part of the equipment for sinking oil, gas, and like wells, and as illustrated, said derrick is of the four-legged type and comprises four upwardly converging corner posts or columns 65 10, 10, each being formed of an equal number of sections 11, 11. The sections 11, 11 of each corner post are placed in vertical or longitudinal alinement and arranged end to end. The derrick is usually erected in units, 70 one upon the other, and each unit has a post section 11 at each of the four corners thereof. The post sections 11, 11 of each unit are equal in length and have their end edges opposed to the end edges of the correspond- 75 ing post sections in the adjacent units. All of the post sections 11, 11 are generally made of lengths of angle-bars, and are connected together at their opposed ends by joint plates, which in the derrick shown are con- 80 structed in accordance with my invention and will be hereinafter referred to and described in detail. The ends of the post sections 11, 11 of each unit are further connected together around the four sides of the 85 derrick by a set of horizontal struts 12, 12, the four struts of each set being arranged in the same horizontal plane and serving to maintain the corner posts 10, 10 spaced apart laterally the required distance. As shown 90 in said Fig. 1, there is a set of four struts 12, 12 connecting the upper ends of the post sections 11, 11 of the base or bottom unit, and a set of a like number of struts connecting the upper ends of the post sections of 95 each of the units above the base one. The set of struts connecting the upper ends of the post sections of one unit also serve to connect the lower ends of the post sections of the unit thereabove. Each unit is further 100 provided on each of the four sides of the derrick with two diagonally arranged tie-rods 13, 13, the latter crossing each other substantially at the center thereof. The cor- 105 responding ends of the struts and tie-rods terminate at and are connected with the joint members referred to. As customary, the upper ends of the corner posts 10, 10 are connected or tied together by the connecting members 14, 14 of a top frame, to which is 110

bolted the crown block in which the crown pulleys 15 are journaled. So much of the derrick structure described and shown is common to such types of derricks, and forms no part of my invention.

In order to insure that a structural steel derrick will possess the desired resiliency and will thereby yield or give under the vertical strains and loads to which the derrick

10 may be subjected during the operations of drilling and hoisting, I connect the several parts of the derrick by joint members 16, 16, constructed in accordance with my invention. As all the joint members 16 em-

15 ployed throughout the derrick are exactly alike in construction, a description of one will suffice for all. As shown in Figs. 2 to 5, each post section 11 is made of a length of angle-iron, and has two integral webs 17,

20 18 arranged substantially at right angles to each other, and, when erected, the angular spaces between said webs open inside of the derrick. The joint member 16 is preferably made of cast metal, angular in cross-section

25 and having two integral webs 19, 20 arranged substantially at right angles to each other, the angle between said webs 19, 20 being complementary to the angle between the webs of the post sections 11, 11. Said

30 webs 19, 20 extend the full length of the joint member 16, and arranged between the ends of the latter is a transverse web or plate 21, which as shown is triangular in shape and extends into and fills the space 35 between the webs 19, 20. Said transverse web 21 is preferably cast integral with the webs 19, 20 between which it extends.

In use, said joint member 16 is applied over the outer faces and at opposed end por-

40 tions of two vertically alined post sections 11, 11, with the webs 19, 20 of said joint member overlapping the webs 17, 18 of said two post sections 11, 11. The joint member 16 is so applied that its transverse web 21

45 extends inward and between the opposed end edges of said two post sections 11, 11, as shown in Fig. 3, and thereby separates the opposed end edges of said post sections. Said opposed end edges abut endwise against

50 said transverse web, and, as shown in Fig. 3, the lower end of the section 11 above the transverse web 21 bears or abuts downward against the upper face of said transverse web 21, while the upper end of the section

55 11 below said transverse web bears or abuts upward against the under side of the same. The portions of the webs 19, 20 above said transverse web 21 overlap the outer surfaces of the webs of the upper section 11, while

60 the portions of said webs 19, 20 below said transverse web 21 overlap the like faces of the lower post section 11. The overlapping webs of the post sections 11, 11 and joint member 16 are clamped together by fasten-

65 ing members, preferably in the form of bolts

22, 22 extending transversely of such parts and inserted through registering bolt holes 23, 24 in said webs. As shown in the drawings, there are four bolt holes 23, 23 in each of said webs 19, 20, two on each side of said transverse web 21. There are two bolt holes 24, 24 in each of the webs 17, 18 of each of said post sections 11, 11, and as shown said bolt holes 24, 24 are elongated vertically or lengthwise of said post sections. In order to prevent the nuts 25, 25, on the inner threaded ends of said bolts 22, 22, from entering said elongated slots 24, 24, an angle-plate 26 is applied against the inner faces of the post sections 11, 11 on each side 80 of the transverse web 21, and said nuts 25 are tightened against said plates.

The advantages arising from the use of my joint members 16 are manifold. In the first place, by the provision of said elongated slots 24, 24, even when the parts are clamped together by the bolts 22 a relative amount of vertical movement or play is permitted between the post sections 11 and the joint members, thereby imparting a degree of flexibility to the derrick structure and allowing the same to yield or give under the vertical loads and strains to which the derrick is subjected during the operations of drilling and

95 hoisting. When drilling a well by the percussive method, the derrick is subjected intermittently to a vertical load or strain as the string of tools is raised and lowered. Consequently, said slots 24, 24 permit the derrick parts to yield vertically and compensate for the vertical loads thus placed

100 upon the post sections 11, and also relieve the clamp bolts 22, 22 from such loads, the latter being transmitted directly to the transverse webs 21. Thus the strength of

105 the derrick is not limited to the shearing stress of the clamp bolts 22, 22. Moreover said transverse webs 21 form relatively wide bearing surfaces for the ends of the post sections 11, 11, and prevent the vertical load on

110 one section from being directly imparted to the corresponding adjacent one, as would be the case if the opposed ends of the post sections abutted endwise one against the other. Then again, said transverse webs 21 and

115 vertical webs 19, 20 of the joint members, together with the bolts 22, 22, hold the ends of the post sections from both lateral and vertical displacement and thereby relieve the bolts 22, 22 from all vertical strains and,

120 further, prevent the opposed ends of the post sections from slipping one past the other, which if permitted would effect the shearing of the clamp bolts under overloads placed upon the derrick. When pulling the

125 casing, there is an extreme downward load placed upon the derrick, and such load is increased if the casing sticks in the well hole due to the presence of some obstruction in the path of upward movement thereof. If

130

such an obstruction is encountered and prevents the casing from being pulled upward, the casing, which is formed of pipe sections coupled end to end, will expand or lengthen 5 endwise under the upward pull thereon. After the casing has stretched to its fullest extent, it suddenly recoils or "comes back," that is, contracts endwise, with the attendant result that the derrick structure is subjected 10 suddenly to a downward overload. This sudden contraction produces a heavy downward overload on the derrick structure, and the latter due to the elongated slots 24, 24, will yield or give commensurate therewith 15 and withstand the same without bending or toppling over or shearing off the bolts 22, 22. The failure of structural steel derricks or towers used in sinking oil, gas, and like wells is directly traceable to the sudden overload 20 being produced by the instantaneous contraction of the casing, and in such derricks the maximum of vertical strength is measured by the shearing strength of the bolts used for clamping the post sections together. 25 In my device, however, ample provision is made for the derrick to withstand this sudden overload, and the derrick possesses all of the advantages of both the structural steel derrick and a wooden one, with the 30 elimination of all of the disadvantages of each.

The horizontal struts 12, 12 of each set are connected at their ends with the four joint members 16 in the same horizontal 35 plane with said set of horizontal struts. The connection is made as follows: As shown in Figs. 2 to 6, the transverse web 21 is provided with two outwardly extending integral parts 27, 27, one adjacent each web 19, 20 40 and arranged in the same horizontal plane as said transverse web. Each strut 12 is made of a length of angle-bar, as shown in Fig. 3, and applied in the derrick structure with one web 28 arranged vertically and extending 45 downwardly, and with the other web 29 arranged horizontally and extending inwardly. The end portion of the horizontal web 29 overlaps the part 27, and is secured thereto by vertically arranged clamp bolts 50 30, 30 having clamp nuts 31, 31 threaded upon the lower ends thereof. The end of the vertical web 28 terminates short of the horizontal web 29 and abuts endwise against the adjacent vertical edge of the joint web 55 19, 20. By reason of this construction, the compressive strains on the strut 12 are transferred or imparted directly to the vertical webs of the joint member 16, thus relieving the clamp bolts 30, 30 of such strains. Moreover, the construction thus described forms 60 a rigid bench or frame at each of the ends of the post sections, and effectively insures the derrick withstanding all of the lateral strains to which it may be subjected. The 65 tie-rods 13, 13 are also connected at their

ends with the associated joint members 16, 16. As shown in Figs. 1 and 5, the upper ends of the tie-rods on one face of one unit terminate adjacent the lower ends of the tie-rods on the same face of the adjacent 70 unit. Each vertical web 19, 20 is provided on each side of the transverse web 21 with two outwardly projecting lugs or bosses 32, 32, the latter being preferably made integral with said webs. Each lug 32 is provided 75 with a hole 33 extending therethrough and arranged at an inclination corresponding with the inclination of the tie-rod having its threaded end inserted through said hole 33. A clamp nut 34 is applied upon the projecting end of the tie-rod for clamping the same to said lug. As shown in Fig. 5, said lugs are staggered, so that one will not act as an obstruction to the wrench used in tightening the nuts upon the ends of the 80 tie-rods.

While I have shown and described said joint member 16 as being used in a derrick structure of the kind referred to, yet it is of course to be understood that said joint member may be used in other structures wherein it is desired to connect two aligned members 90 together.

The other advantages arising in the use of my joint member 16 will be apparent to 95 those skilled in the art to which this invention appertains, and, although I have shown and described herein one preferred form of joint member embodying the features of my invention, yet it is to be of course understood 100 that the details of construction and arrangement of parts shown may be variously changed and modified without departing from the spirit and scope of my invention, and I do not wish to be limited to the exact 105 details of construction shown, except as hereinafter claimed.

I claim as my invention:

1. The combination with two vertically aligned bars arranged end to end, of a joint 110 member for connecting the opposed ends of said bars together, said joint member having a transverse web extending between and separating the opposed ends of said bars, said joint member being provided with a 115 vertical web having portions extending on opposite sides of said transverse web and overlapping the end portions of the bars, two clamp plates, one on each side of said transverse web and applied against those side 120 faces of said bars opposite the side faces thereof overlapped by said vertical web, said vertical web and plates being provided with aligned bolt holes, and the end portions of the bars between said vertical web and plates 125 being provided with vertically elongated slots, and clamping bolts inserted through said bolt holes and slots.

2. A frame structure of the character described, comprising upright corner posts, 130

each being formed of a plurality of vertically alined sections, a joint member for connecting the opposed ends of each two sections together, said joint member having a transverse web extending between and separating the opposed ends of said sections, said joint member being provided with a vertical web having portions extending on opposite sides of said transverse web and overlapping the end portions of the sections, two clamp plates, one on each side of said transverse web and applied against those side faces of said sections opposite the side faces thereof overlapped by said vertical web, said vertical web and plates being provided with alined bolt holes, and the end portions of the

sections between said vertical web and plates being provided with vertically elongated slots, clamping bolts inserted through said bolt holes and slots, and a longitudinal strut extending between said posts and connected at its ends with the transverse webs of the joint members between which it extends.

In testimony that I claim the foregoing as my invention, I affix my signature in the presence of two witnesses, this 22nd day of May, A. D. 1916.

CLAYTON E. FREDERICKSON.
